LOW FREQUENCY MODULATION EXPANDER

Don G. Burnside, East Orange, N. J., assignor to
Radio Corporation of America, a corporation of
Delaware

Application April 18, 1939, Serial No. 268,464

10 Claims. (Cl. 250—20)

My present invention relates generally to audio frequency tone control circuits, and more particularly to a novel method of securing automatic bass compensation in an audio frequency transmission network.

It is known that the human ear is relatively insensitive to sounds of low frequency when the sound intensity is of low value. Whenever it becomes necessary to reduce the volume level of reproduced sound, it sounds to the listener's ear as though there is a serious deficiency in the reproduction of bass notes. This effect arises even though the modulation frequency voltage amplifier be capable of passing the various audio frequency voltage components without altering their relative amplitudes. As is well known, many devices have been employed to augment the bass response of reproduced sound so that the psychological effect of true tone balance is secured.

Now I have devised a novel method of, and means for, automatically securing bass compensation in an audio network; the method taking advantage of the fact that in most broadcast transmitters the low frequency audio signals modulate the carrier wave to a higher degree than do the high frequency audio signals.

It may be stated to be one of the main objects of my present invention to arrange a pair of modulated carrier energy rectifiers in opposition so that they produce no direct current output with applied unmodulated carrier of constant or varying amplitude, but give a direct current output dependent on the modulation of the carrier.

Another important object of my invention is to provide opposed signal rectifiers in a modulated carrier energy detector network, the detector providing audio voltage for a subsequent audio network and direct current voltage whose magnitude is dependent on the degree of modulation of the carrier.

Another object of this invention is to provide in combination with a diode signal detector feeding audio voltage to an audio amplifier, a second diode detector arranged in opposition to the first detector thereby to provide a direct current voltage which increases in magnitude, and in a positive polarity sense, with the degree of modulation of the signal carrier by the low audio frequencies, and the direct current voltage being applied to the audio amplifier in a gain-increasing sense whereby bass compensation is secured.

The novel features which I believe to be characteristic of my invention are set forth in partic-

ularity in the appended claims; the invention itself, however, as to both its organization and method of operation will best be understood by reference to the following description taken in connection with the drawing in which I have indicated diagrammatically several circuit organizations whereby my invention may be carried into effect.

In the drawing—

Fig. 1 illustrates a simple detector network embodying the invention,

Fig. 2 shows a detector-audio amplifier arrangement embodying the invention.

Referring now to the accompanying drawing, and specifically to Fig. 1, there are shown a pair of diodes 1 and 2 having a common carrier input source. The latter may be the output circuit of any pre-detector network of a radio receiver, and the resonant circuit 3 is coupled to the carrier source and is tuned to the operating carrier frequency.

Let it be assumed that upon circuit 3 is impressed audio modulated carrier energy, and that the carrier amplitude is maintained substantially uniform at the circuit 3 by any well known type of automatic volume control circuit. The diode 1 has its anode 4 connected to cathode 5 through a path including circuit 3 in series with a load resistor 6, a condenser 7 being shunted across the resistor. The diode 2 has its anode 8 connected to cathode 9 through a series path comprising the carrier choke coil 10 and load resistor 11, and condenser 12 is connected across the resistor. The junction of coil 10 and resistor 11 is grounded, and carrier energy is impressed on anode 8 by the condenser 13 connected between the high potential end of circuit 3 and anode 8.

Current indicator devices may be included in series with each diode load resistor to indicate current flow in each rectifier. The audio network, utilizing the audio voltage output of the demodulator, is shown as connected between ground and the anode end of resistor 6. The diodes may be housed in a single tube envelope if desired.

The resistors 6 and 11 have equal resistive magnitudes, and both condensers 7 and 12 have low impedances to carrier frequency current. Hence for carrier only, the product of the current through resistor 6 and resistance of the latter is equal to the product of the current through resistor 11 and resistance of the latter. Therefore the direct current voltages, for an unmodulated carrier, across the load resistors 6 and 11 are equal in value and opposite in polarity. It

will then be seen that the direct current voltage between terminals A remains unchanged. If, now, the carrier energy applied to the diodes be modulated the direct current voltage across resistor 6 is but slightly altered, since condenser 7 is small (of the order of 100 micromicrofarads (mmf.). The same modulated carrier applied to diode 2 causes condenser 12 to charge to the peaks of the modulated carrier, because condenser 12 is larger as compared to condenser 7. Condenser 12 may have a magnitude of about 1 mfd. (microfarads). Accordingly, the direct current voltage across resistor 11 is increased, reaching twice that across resistor 6 with 100% modulation. The direct current voltage at terminals A becomes increasingly positive as a result, since one terminal of A is at ground and the other is connected to the cathode end of resistor 11. Audio voltage, also, appears at A by virtue of demodulation by diode 1; diode 2 causes no production of audio voltage because of the larger value of condenser 12. Condenser 13 permits only carrier voltage to be applied to diode 2, and coil 10 prevents loss of carrier voltage. The device operates to provide equal voltages across resistors 6 and 11 with carrier only, regardless of its amplitude. The direct current voltage across resistor 6 is the carrier peak voltage times the rectification efficiency, as it is across 11. With the carrier modulated the direct current voltage across 11 is more nearly the peak of the envelope times the rectification efficiency. The voltage across resistor 11 is thus over and above that across resistor 6.

The direct current voltage and audio voltage developed at A can be used in any audio amplifier network. More specifically, the direct current voltage is employed to increase the gain of the audio amplifier. When the volume level of the sound output of the audio amplifier is reduced to a point where normally a reduced bass response seems to occur, the effect of the direct current voltage at A will be to augment the audio gain and thereby compensate for the lowered bass response. In Fig. 2 is shown a specific circuit embodying the bass response augmenting network. It is assumed that the network is embodied in a superheterodyne receiver, and that input circuit 14 is the intermediate frequency output circuit of the last intermediate frequency amplifier. The circuit 14 is coupled to the demodulator, or detector, input circuit 15 which is similarly resonated to the operating intermediate frequency. The diode 16 has its anode connected to its cathode through a path including circuit 15 and load resistor 17; carrier by-pass condenser 18 shunting resistor 17. Diode 19 has its anode connected to its cathode through a path comprising choke coil 20 and load resistor 21; carrier by-pass condenser 22 shunting the resistor 21. The condenser 23, of low impedance to the intermediate frequency currents, couples the anode of diode 19 to the input circuit 15.

The cathodes of the diodes 16 and 19 are connected together, and a single tube envelope embodying the electrodes of a pair of diodes may be used. The anode end of resistor 21 is returned to ground by a lead 24. The lead 24 is connected to point 25 on the voltage supply resistor 26. An intermediate point 27 of resistor 26 is established at ground potential, and point 25 may be a point on the resistor which is negative with respect to ground. It is to be understood that the resistor 26 may be connected across the usual power sup-

ply network of a commercial broadcast radio receiver.

The audio voltage developed across resistor 17 is impressed upon the control grid 28 of tube 29. The cathode of tube 29 is connected to ground through a path which includes a resistor 30, and the signal grid 28 is connected to an intermediate point 31 on the cathode resistor 30 through a path which includes the grid leak resistor 32. The audio voltage connection to grid 28 includes the audio coupling condenser 33, and adjustable tap 34 provides control over the amplitude of the audio voltage impressed upon signal grid 28. In other words tap 34 provides the manual volume control device of the system. It will be understood that resistors 17 and 21 are of equal magnitude, and that while condensers 18 and 22 are bypass condensers for the intermediate frequency carrier, the magnitude of condenser 22 exceeds that of condenser 18. In other words audio voltage is developed across load resistor 17 due to rectification by diode 16, while no audio voltage is developed across resistor 21 due to the fact that the magnitude of the capacitance of condenser 22 is considerably larger than that of condenser 18. Condenser 22 can have a value of 1 mfd. However, there is developed across resistor 21 a direct current voltage whose magnitude is proportional to the degree of modulation of the intermediate frequency carrier, and this is caused by the fact that the modulated carrier applied to diode 19 through condenser 23 causes condenser 22 to charge to the peaks of the modulated carrier. The direct current voltage developed across resistor 21 reaches twice that across resistor 17 with 100% modulation.

The plate of audio tube 29 is connected to a proper positive potential point on resistor 26 through a load resistor 40. The tube 29 functions as a phase changing amplifier tube, the audio voltage output of tube 29 being impressed upon a pair of tubes 41 and 42 arranged in push-pull connection. Each of the push-pull amplifier tubes may be of the 6L7 type. Tube 41 includes a cathode and an output electrode, as well as five grid electrodes. The first, or signal, grid 43 is connected to a desired point on load resistor 40 through a path which includes the audio coupling condenser 44 and the adjustable tap 45. The signal grid 46 of tube 42 is connected to a desired point on the cathode load resistor 30 through a path which includes audio coupling condenser 47 and the adjustable tap 48.

In order to provide normal negative bias for the signal grids 43 and 46, a resistor 50 connects the two grids and the mid-point of the resistor is connected by lead 51 to a point 52 on voltage supply resistor 26 which is negative with respect to ground point 27. Since the cathodes of tubes 41 and 42 are established at ground potential, it will be seen that the connection to point 52 provides the normal negative bias for the signal grids 43 and 46 thus permitting operation of tubes 41 and 42 as audio amplifiers. The plate electrodes of tubes 41 and 42 are connected in common to the opposite ends of the primary winding of the audio output transformer T, and the midpoint of the primary winding may be connected to a desired positive potential point on supply resistor 26. It is to be understood that the secondary winding of transformer T will be connected to any desired type of audio reproducer device.

The third grid, with respect to the cathode, of tube 41 is denoted by numeral 60, and it is con-

nected by lead 61 to the anode end of load resistor 17, the lead including a filter resistor 62. Similarly, the third grid 70 of tube 42 is connected by lead 71 to the filter resistor 62. The grids 60 and 70 function as the gain control electrodes of tubes 41 and 42 respectively, and they are both connected to the anode end of resistor 17 so that they will be unaffected by unmodulated carrier energy impressed on diodes 16 and 19. For modulated intermediate frequency carrier energy the grids will be biased in a positive polarity sense by the direct current voltage developed across resistor 21, it being noted that effectively the grids 60 and 70 are connected to the cathode end of resistor 21. Further it will be noted that normal negative bias is applied to grids 60 and 70 by virtue of the connection of these grids to point 25, this connection being through resistors 17 and 21 and lead 24. Point 25 is negative with respect to point 52, and, therefore, there is a normal negative bias applied to grids 60 and 70 such that the mutual conductance of each tube is at a relatively low value for unmodulated carrier energy.

The gain control electrodes of each of tubes 41 and 42 are located between a pair of positive screen grids, and these pairs of screen grids may be connected to a common positive potential point on the resistor 26, as is well known to those skilled in the art. Furthermore, each of the suppressor grids of the tubes 41 and 42 may be established at ground potential. The direct current voltage connections 61 and 71 provide the automatic bass compensation. The audio voltage applied to the signal grids 43 and 46 are of suitable phase for push-pull operation, since the audio voltage for grid 43 is derived from the plate load resistor of tube 29, while the voltage for grid 46 is derived from the cathode load resistor 30. When the tap 34 is adjusted for impression of audio voltage of maximum magnitude on grid 28, then it will be understood that there is little need for the bass compensation action since to the listener's ear there will not appear any deficiency of the intensity of reproduction of the bass notes. However, when the tap 34 is adjusted for impression of audio voltage of minimum amplitude on grid 28 then the automatic bass compensation is effective.

The bass compensation is effected by virtue of the fact that the low audio frequencies modulate the intermediate frequency carrier to a much greater extent than the high audio frequencies. Hence, there is developed across resistor 21 a direct current voltage whose magnitude is proportional to the degree of modulation of the intermediate frequency carrier and, therefore, the magnitude of the direct current voltage developed across resistor 21 exceeds the value of the direct current voltage developed across resistor 17. Because of this fact a direct current voltage is applied to grids 60 and 70 which is positive in polarity. This positive voltage acts to reduce the high negative bias applied from point 25, and the gain of each of tubes 41 and 42 is increased. It will, therefore, be seen that for adjustment of the audio network to reduce volume level, there occurs the compensating increase in the gain of each audio amplifiers 41 and 42. This increase in gain will be sufficient to compensate for the apparent impairment of the reproduction of the bass notes.

While I have indicated and described several systems for carrying my invention into effect, it will be apparent to one skilled in the art that my invention is by no means limited to the par-

ticular organizations shown and described, but that many modifications may be made without departing from the scope of my invention, as set forth in the appended claims.

What I claim is:

1. In a system for detecting audio modulated carrier waves which includes means for rectifying a portion of the waves to produce audio modulation voltage and a unidirectional voltage whose value is independent of the modulation degree of the carrier, means for rectifying a second portion of the waves to produce a second uni-directional voltage whose magnitude is dependent on the degree of modulation of the carrier, means combining the two voltages in polarity opposition, means utilizing the audio modulation voltage output of said first rectifying means, and means utilizing the said resultant combined voltage to control the said audio utilizing means.

2. In a system for receiving audio-modulated carrier energy which includes means for detecting a portion of the energy to produce audio voltage and a direct current voltage whose magnitude is dependent solely on the carrier amplitude, means for detecting a second portion of the energy to produce a direct current voltage whose magnitude is dependent on both the carrier amplitude and the degree of modulation of the carrier, means combining the two direct voltages to produce a control voltage whose value increases with the increase of the degree of modulation of the carrier, means for amplifying said audio voltage and means for expanding the gain of the amplifying means in response to increase in magnitude of said control voltage.

3. In a system of receiving audio-modulated carrier energy which includes means for detecting a portion of the energy to produce audio voltage and a direct current voltage whose magnitude is dependent solely on the carrier amplitude, means for detecting a second portion of the energy to produce a direct current voltage whose magnitude is dependent on both the carrier amplitude and the degree of modulation of the carrier, means combining the two direct voltages to produce a control voltage whose value increases with the increase of the degree of modulation of the carrier, means for amplifying the audio voltage, and means for controlling the amplification of the audio voltage with said control voltage.

4. In a system of detecting audio modulated carrier waves which includes means for rectifying a portion of the waves to produce a unidirectional voltage whose value is independent of the modulation degree of the carrier, means for rectifying a second portion of the waves to produce a second uni-directional voltage whose magnitude is dependent on the degree of modulation of the carrier, means for combining the two voltages in polarity opposition, means for deriving an audio voltage from solely the said first portion of carrier waves, means transmitting the audio voltage through an audio network, and means increasing the transmission efficiency through said audio network in response to said resultant voltage.

5. In combination, in a modulated carrier receiving system, a pair of detectors, each detector including a load resistor, one of said load resistors having means operatively associated therewith whereby an audio voltage is developed across the resistor, means operatively associated with the other load resistor whereby a direct

current voltage is developed across the resistor which is proportional to the degree of modulation of a carrier, an audio amplifier including means for impressing thereon the said audio voltage, means for regulating the magnitude of said impressed audio voltage, and additional means for increasing the gain of said audio amplifier in accordance with an increase in the magnitude of the aforesaid direct current voltage.

6. In combination, in a modulated carrier receiving system, a pair of detectors, each detector including a load resistor, one of said load resistors having means operatively associated therewith whereby an audio voltage is developed across the resistor, means operatively associated with the other load resistor whereby a direct current voltage is developed across the resistor which is proportional to the degree of modulation of a carrier, an audio amplifier including means for impressing thereon the said audio voltage, means for regulating the magnitude of said impressed audio voltage, and additional means for controlling the gain of said audio amplifier with the aforesaid direct current voltage, said audio amplifier including a signal grid having a connection to said load resistor across which the audio voltage is developed, and a second connection from the audio amplifier to said resistor across which is developed said direct current voltage whereby the latter voltage is transmitted over said second connection.

7. In combination, in a modulated carrier receiving system, a pair of diode detectors, each detector including a load resistor, one of said load resistors having means operatively associated therewith whereby an audio voltage is developed across the resistor, means operatively associated with the other load resistor whereby a direct current voltage is developed across the resistor which is proportional to the degree of modulation of a carrier, an audio amplifier including means for impressing thereon the said audio voltage, means for regulating the magnitude of said impressed audio voltage, and additional means for controlling the gain of said audio amplifier with the aforesaid direct current voltage, said audio amplifier including a signal grid and a gain control grid, an audio voltage connection between the signal grid and said re-

sistor which develops said audio voltage, and an independent connection between said gain control electrode and said resistor which develops said direct current voltage.

8. In an audio-modulated carrier wave receiving system, a pair of rectifiers having a common carrier wave input circuit, means operatively associated with said rectifiers for deriving from rectified modulated carrier wave current a unidirectional voltage, whose magnitude is a function of the degree of modulation of the carrier, and an audio modulation voltage, amplifier means utilizing said modulation voltage, and means responsive to increase in magnitude of said unidirectional voltage for controlling said utilizing means in a gain-increasing sense.

9. In an audio-modulated carrier wave receiving system, a pair of rectifiers having a common carrier wave input circuit, means operatively associated with said rectifiers for deriving from rectified modulated carrier wave current a unidirectional voltage, whose magnitude is a function of the degree of modulation of the carrier, and an audio modulation voltage, means utilizing said modulation voltage, and means responsive to said unidirectional voltage for controlling said utilizing means, and said utilizing means comprising a pair of audio amplifier tubes arranged in push-pull relation, means for adjusting the magnitude of the audio voltage impressed upon said amplifier tubes, and said controlling means being connected to said amplifier tubes to increase the gain thereof in response to an increase in magnitude of said unidirectional voltage.

10. In an audio-modulated carrier wave receiving system, a pair of rectifiers having a common carrier wave input circuit, means operatively associated with said rectifiers for deriving from rectified modulated carrier wave current a unidirectional voltage, whose magnitude is a function of the degree of modulation of the carrier, and an audio modulation voltage, means utilizing said modulation voltage, and means responsive to an increase in magnitude of said unidirectional voltage for increasing the volume level of said receiving system.

DON G. BURNSIDE.
